UNITED STATES PATENT OFFICE

KENT A. HAWLEY, OF BALTIMORE, MARYLAND, ASSIGNOR TO LOCKE INSULATOR CORPORATION, OF BALTIMORE, MARYLAND, A CORPORATION OF MARYLAND

INSULATOR

Application filed August 18, 1927. Serial No. 213,859.

The invention relates to insulators, particularly those of what may be called the post pedestal type embodying a plurality of porcelain sections surmounted by a metal 5 cap.

The principal object of the invention is to improve the construction of the top shell or unit of such an insulator whereby the cap will be permitted to fit down more closely, 10 the mechanical strength being thereby increased, and whereby there will be an interfitting effect strongly resisting torsional loading.

It is well known that an insulator of the 15 post pedestal type has its top shell carrying a cap formed with a plurality of holes for the accommodation or reception of cap screws or the like employed for mounting switch bases, bus bars and other elements upon the 20 insulator, the holes being located within thickened portions at the inside of the cap, the extra thickness of metal being necessary on account of the fact that the holes must be tapped. In the ordinary construction of 25 the top shell these thickened portions or lugs as they may be called cause the cap to extend upwardly to an excessive extent, the over all height of the insulator being thereby increased without deriving any advantage, and 30 the mechanical strength being decreased in proportion to the increase in the moment arm in the event that a downward and lateral pressure is applied to the insulator.

It is with the above facts in view that I have 35 designed the present invention which contemplates the provision of a top shell appropriately recessed to accommodate the lugs or thickened portions of the cap in which the tapped holes are provided, the recesses and 40 lugs interfitting and obviously resisting torsional strain, and the reception of the thickened portions within the recesses resulting in a decrease in the height of the insulator.

45 Another object is to provide a top shell of this character which may be peripherally grooved, sanded or otherwise roughened to insure a proper grip of the cement for securing the cap in place, there being no particular 50 limitations in these details inasmuch as the

different methods mentioned are all old and well known.

An additional object is to provide an insulator top shell or unit which will cost no more than one of ordinary type to manufacture 55 and which may be assembled with respect to the adjacent parts as simply and easily as one of conventional pattern.

To the attainment of the foregoing and other objects and advantages, the invention 60 preferably consists in the details of construction and the arrangement and combination of parts to be hereinafter more fully described and claimed, and illustrated in the accompanying drawing in which:

65 Figure 1 is a view partly in side elevation and partly in section showing an insulator of the post pedestal type having a top shell constructed in accordance with my invention.

70 Figure 2 is a fragmentary plan view of the top shell, and

75 Figure 3 is an inside plan view of the cap. Referring more particularly to the drawing I have shown an insulator, or portion thereof, including a lower section or unit 1 and a top shell 2, both being constructed of porcelain as is customary and both likewise possessing the usual characteristics or structural features in so far as skirts and other 80 details are concerned. The lower section 1 is shown as recessed at 3 for mounting upon the usual pin, not shown, which would be cemented in place. The numeral 4 designates the metal cap which is circular in shape 85 and of a cup-like form to fit over the upstanding stem portion 5 of the top shell. In insulators of this type the cap is provided with a plurality of holes 6, generally four in number, for the reception of cap screws or the like used in mounting switch bases or other elements upon the insulator. The holes are necessarily tapped and for this reason the cap is formed at the holes with thickened portions 90 or lugs 7 which are on the underside of the top. There is nothing peculiar about the cap in so far as the present invention is concerned and it is customary to secure the cap upon the upstanding stem portion 5 of the top shell by means of cement indicated at 95

100

8, the inner periphery of the cap being usually grooved and the outer periphery of the up-standing stem portion of the top shell being horizontally grooved, as illustrated in the drawing, or else sanded or otherwise roughened in order to insure a firm grip and strong joint between the cap and shell. The sanded construction is not illustrated inasmuch as it is so well known and as it is not any part of the invention.

10 In the ordinary construction of top shell the thickened portions or lugs 7 would come down upon the upper surface of the top shell and there is consequently quite a large mass of cement filling the space between the shell and cap. Thermally large masses of cement are objectionable and in the present instance such are eliminated. What may be considered the feature of the present invention is 15 the provision of a plurality of recesses 9 in the top of the shell 2, these recesses being of at least slightly greater size than the thickened portions or lugs 7 so as to receive them readily and to leave sufficient space to be occupied by the cement. The exact shape of the recesses 9 may of course be varied as it is not an important consideration, but generally speaking they would probably be of the same or substantially the same contour 20 as the lugs or thickened portions.

Assembly is effected in the ordinary manner and the insulator will have the same general appearance as those heretofore constructed except that the cap will come lower 25 upon the top shell as the lugs or thickened portions are received within the recesses. The over all height is thus decreased with a corresponding increase in mechanical strength inasmuch as the moment arm is reduced. Furthermore the interfitting of the lugs and recesses will provide such an interlock as will 30 positively resist torsional strains tending to rotate the cap with respect to the top shell. These advantageous mechanical features are 35 obtained without in any way detracting from the electrical strength or materially increasing the cost of production. From the foregoing it is believed that the construction, operation and advantages will be readily apparent to one skilled in the art without further explanation.

40 While I have shown and described the preferred embodiment of the invention, it should be understood that the disclosure is merely an 45 exemplification of the principles involved as the right is reserved to make all such changes in the details of construction as will widen the field of utility and increase the adaptability of the device provided such changes 50 constitute no departure from the spirit of the invention or the scope of the claims hereunto appended.

Having thus described the invention, I claim:

55 1. In a multi-part insulator, a plurality

of porcelain shells arranged in superposed relation, a cap for the topmost shell having a plurality of lugs on its inner underside, the topmost shell having recesses therein accommodating said lugs.

2. In a multi-part insulator, a plurality of porcelain shells arranged in superposed relation, a cap for the topmost shell having a plurality of lugs on its inner underside, the topmost shell having recesses therein accommodating said lugs and conforming substantially thereto.

3. In an insulator, a plurality of dielectric shells and a metal cap mounted upon the topmost shell, the cap having thickened portions at its underside and tapped holes in said thickened portions, and said topmost shell having recesses in its top receiving said thickened portions.

4. In an insulator, a porcelain section having an upstanding stem portion formed in its top surface with a plurality of recesses, and a metal cap secured upon said stem portion and having the underside of its top provided with depending thickened portions constituting lugs and provided with tapped holes, said thickened portions being received within said recesses whereby to provide resistance to torsional loading and to decrease the moment arm in the event of the application of lateral pressure upon the cap with respect to the porcelain member.

In testimony whereof I affix my signature.

KENT A. HAWLEY.
